DESIGN FOR A COMBINED BRACKET AND VASE

Louis Alexander Lindey, Brooklyn, N. Y.

Application March 12, 1940, Serial No. 90,849

Term of patent 7 years

To all whom it may concern:

Be it known that I, Louis Alexander Lindey, a citizen of the United States, residing at Brooklyn, in the county of Kings and State of New York, have invented a new, original, and ornamental Design for a Combined Bracket and Vase, of which the following is a specification, reference being had to the accompanying drawing, forming part thereof.

I claim:

The ornamental design for a combined bracket and vase, as shown.

LOUIS ALEXANDER LINDEY.
